UNITED STATES PATENT OFFICE.

STURGES WHITLOCK, OF SHELTON, ASSIGNOR TO THE WHITLOCK MACHINE COMPANY, OF BIRMINGHAM, CONNECTICUT.

FORM-ROLLER MECHANISM FOR PRINTING-MACHINES.

SPECIFICATION forming part of Letters Patent No. 416,820, dated December 10, 1889.

Application filed November 18, 1888. Serial No. 290,672. (No model.)

To all whom it may concern:

Be it known that I, STURGES WHITLOCK, a citizen of the United States, residing at Shelton, in the county of Fairfield and State of Connecticut, have invented certain new and useful Improvements in Form-Roller Mechanism for Printing-Machines; and I do hereby declare the following to be a full, clear, and exact description of the invention, such as will enable others skilled in the art to which it appertains to make and use the same.

My invention relates to certain new and useful improvements in form-rollers for printing-presses, but more particularly does it appear to an improved journal-bearing in which the distributor for the form-rollers may be supported and securely held, and from which it may be released quickly and easily, and to a simple and compact mechanical device whereby a traverse in the direction of its length may be regularly and automatically imparted to the said distributor; and with these ends in view my invention consists in the construction and arrangement of parts and the combination of elements, such as will be hereinafter more fully set forth and then specifically designated by the claims.

In order that those skilled in the art to which my invention appertains may more fully understand the nature, construction, and use of my improvement, I will describe the same in detail, reference being had to the accompanying drawings, which form a part of this specification, and in which—

Figure 1 is a perspective of the form-rollers, the distributor, and the mechanism for operating them, a portion of the bed and of the standard being shown; Fig. 2, a front elevation of the distributor and one form-roller, the journals being sectioned centrally, vertically, and longitudinally on the line $x-x$ of Fig. 1; and Fig. 3, a transverse vertical section through the distributor-roll journal and block, taken at the line $y-y$ of Fig. 2.

Like reference-numerals denote the same parts in all the figures of the drawings.

1 represents the base or frame-work upon which the moving parts of the machine are mounted, as in ordinary presses, and 2 is a standard bolted or otherwise firmly secured upon the edge of said frame-work.

3 is the reciprocating bed, adapted to con-

tain the form, and 4 is a rack arranged at the edge of said bed and extending longitudinally thereof. The standard has arranged thereon suitable bearings 5, wherein are journaled the form-rollers 6 7, which apply the ink to the form as it passes beneath them. The opposite ends of the form-rollers are similarly journaled in bearings mounted on another standard 8 at the other side of the bed.

9 is the distributor-roll, journaled in a plane higher than the plane of the form-rollers and engaging with them. Its function is that usual to distributors—namely, to equalize the ink upon the form-rollers, so that it shall be evenly applied to the face of the form by said rollers. Said distributor is preferably of metal, and upon its shaft 10 is mounted the gear 11, whereby it is driven, as will be presently explained. Beyond the said gear the shaft is held by means of a cap and screw 12 in a sleeve 13, which forms a bearing wherein said shaft may turn. This sleeve is cut away, as at 14, to form two parallel faces, one upon each side thereof, thereby to all intents and purposes squaring the sleeve at that point.

15 is a movable block connected to the standard 2 by means of pins 16, which are free, as will be hereinafter set forth, to slide longitudinally in bearings in said standard. At the top of this block is a square yoke 17, which is adapted to receive the squared or faced portion of the sleeve, so as to hold the latter as against rotation and also against longitudinal movement independent of said block. Any lifting of the sleeve and shaft journaled therein—as, for instance, by the raising of the form-rollers—except where it is desired to remove the distributor-roll, is obviated by a latch 18, whose upper end is open and embraces the sleeve, and which is retained normally in its closed position (see Figs 1 and 2) by means of a spring 19, acting upon its lower end below the pivotal point thereof. (See Fig. 2.) The other end of the shaft of the distributor-roll passes through and has its bearing in a hinged block 20 at the farther side of the bed.

The distributor has imparted to it both a rotary movement in its bearings and an endwise reciprocation, and the means whereby these functions are effected are as follows:

21 is a pinion secured upon a sleeve 22,

which latter has a bearing in the standard 2, as seen at Fig 2. This pinion meshes with and is driven by the rack 4 on the edge of the bed, and said pinion in its turn meshes with the gear 11 on the distributor-roll shaft, and thereby imparts motion to the roll. The said sleeve 22 is interiorly threaded, and a screw 23, whose outer end is firmly secured to the block 15, (see Fig. 2,) engages the interior threaded surface of the sleeve. In the operation of my improved machine the backward and forward movement of the bed, through the rack pinion and gear, imparts the rotary movement to the distributor-roll, first in one direction and then in the other, the form-rollers meanwhile being rotated by their engagement with the face of the form. As the rack-driven pinion 21 revolves, the sleeve 22 upon which it is secured also revolves, and therefore, since the sleeve and pinion turn always in the same vertical plane, the screw 23 is driven longitudinally inward or outward, according as the pinion is being driven forward or backward by the rack. The screw, according to its movement, carries the block 15 inward or outward upon the bearing-pins 16, and as the distributor-roll is held in the top of the block against longitudinal movement, except as carried by said block, by the engagement of the squared sleeve with said block said roll acquires a longitudinal reciprocation relative to the form-rollers in addition to its rotary movement upon its bearings. To provide for the proper driving of the roll by the pinion notwithstanding the longitudinal movement of the former, the driven gear 11 is made of a width about as much greater than that of the pinion as the extent of the lengthwise traverse of the roll. The farther end of the distributor-roll shaft is free to slide in its bearing.

In order to remove the distributor-roll from the machine it is only necessary to draw back the spring-actuated latch out of engagement with the end of the sleeve (see dotted lines, Fig. 2) and then raise the sleeve and roll from their engagement with the yoke in the top of the block. (See section, Fig. 3.) The other end of the shaft may then be readily withdrawn out of its bearing in the hinged block, which latter may turn on its hinge, as seen at dotted lines in Fig. 2.

I claim as my invention—

1. The combination, with the distributor-roll, of the sleeve surrounding the roll-shaft and forming a bearing therefor, said sleeve being faced square near its end, the supporting-block having a yoke arranged to embrace the faced section of the sleeve, and a latch engaging the end of the sleeve, whereby said sleeve is held as against movement and

a firm bearing for the shaft afforded, substantially as set forth.

2. In a printing-machine, the combination, with the distributor-roll and the means for driving and traversing the same, of the sleeve fitted over the end of the roll-shaft and faced, as shown, the yoked support engaging the faced portion of said sleeve, and the spring-actuated latch adapted to encircle and hold the extremity of said sleeve, whereby the roll is held in firm bearings, substantially as specified.

3. In a printing-machine, the combination, with the distributor-roll, the faced bearing-sleeve, the yoked support for the latter, and the means for driving and traversing the roll, of the latch pivoted at the side of the supporting-block and adapted to embrace the end of the sleeve, and the spring bearing against the end of the latch and adapted to hold the latter normally in its engaged position, substantially as set forth.

4. In a printing-machine, the combination, with the distributor-roll and the faced sleeve upon the shaft thereof, of the movable block whereon the sleeve is supported, the latch whereby the sleeve is held, and the rack, pinion, threaded sleeve, and screw whereby the movable block is caused to travel toward and away from the bed and the proper traverse imparted to the roll, substantially as and for the purpose specified.

5. In a printing-machine, the combination, with the distributor-roll, of the movable block whereon one end of said roll has a bearing, the rack at the edge of the bed, the pinion and its integral internally-threaded sleeve driven by said rack, the gear on the roll-shaft driven from said pinion, and the screw secured to the movable block and actuated in both directions by the internally-threaded sleeve, whereby said block and roll are traversed, substantially as described.

6. In a printing-machine, the combination, with the distributor-roll and the sleeve in which it has its bearing, of the block whereon said sleeve is supported, the slide bearing-pins secured to the block and having bearings in the standard, wherein they may slide longitudinally, the screw projecting inward from said block, and the threaded sleeve and pinion operated by the rack, and whereby the inward and outward movement of the block is effected, substantially as specified.

In testimony whereof I affix my signature in presence of two witnesses.

STURGES WHITLOCK.
